ATTORNEY

UNITED STATES PATENT OFFICE.

SAMUEL P. SHACKLETON, OF WYOMING, NEW YORK, ASSIGNOR TO AMERICAN TELEPHONE AND TELEGRAPH COMPANY, A CORPORATION OF NEW YORK.

SIGNALING SYSTEM.

Application filed March 15, 1927. Serial No. 175,582.

This invention relates to telephone transmission circuits, and more particularly to signaling arrangements associated therewith.

5 In telephone practice, difficulty is experienced due to poor insulation of conductors, and particularly of conductors contained in central office cabling. This causes faulty operation of lamps or other signals at telephone switchboards. This difficulty is more pronounced under certain atmospheric conditions, and undesired grounded circuits which maintain the lamps or signals in false operated condition occur as a result of such 10 leakage.

It is one of the objects of this invention to provide a simple and efficient signaling circuit which will obviate this difficulty.

Another object consists in providing a 20 discharge tube in connection with the signaling circuits, such, for example, as a neon tube or other tube having similar characteristics, which will cooperate with said circuits.

25 Other and further objects will appear more fully from the following detailed description, when considered in connection with the accompanying drawing, in which one embodiment of the invention is illustrated.

In the drawing, a telephone transmission or toll line is indicated as terminating at different positions in a telephone switchboard. The toll line which is shown for the 30 purpose of illustration, has its conductors represented by the character 5. The transmission line 5 has a plurality of jacks, as shown by the designations 6, 7, 8 and 9, multiplied thereto. Signaling lamps 10, 11, 12 and 13 are associated, respectively, with each of the jacks 6, 7, 8 and 9 for each position. The lighting of lamps 10, 11, and 13 indicate an incoming coil, and the key 14 may be employed in connection with the 35 group of lamps to transfer calls from one position to the other by extinguishing a lamp in one position and lighting a lamp at another position. A group of busy signals is associated with each position, as indicated at 15, 16, 17 and 18. These signals may be used in connection with the jacks 6, 7, 8 and 9, respectively. The signals are represented as being discharge tubes, such as a neon or other tube which will present high resistance under normal conditions, but when a poten-

tial is impressed across the tube sufficient to break down its high resistance, the flow of current is established through the tube which maintains a comparatively low resistance therein. A relay 19 is operated in response 40 to an incoming call over the toll conductors 5 under control relays energized by the transmission of ringing current over the said conductors, as will presently appear. The relay 19 maintains the signals 15, 16, 17 and 18 in operated condition during the call. Contact springs 20 and 21 are associated with the armature of relay 19 and serve to momentarily establish ground potential on the battery side of the tubes to effectively 45 short-circuit them and re-establish the normal high internal resistance of the tubes upon the de-energization of relay 19 at the termination of a call.

In the operation of the improved system, 50 the transmission of ringing current over the line conductors 5 causes the operation of ringing relay 22 which is bridged across said conductors through leads 23 and back contact of relay 24. The energization of relay 22 closes a circuit from its grounded contact, conductor 25, winding of relay 26, conductor 27 to battery through the right contact of relay 24. The closure of this circuit causes the energization of relay 26, which completes a circuit through its make contact from ground, right-hand winding of relay 28 to battery, thus operating the latter relay. The energization of relay 28 closes a locking circuit from ground through its 55 left-hand winding and make contact over conductor 27, contact of relay 24 to battery. A circuit is also closed at this time from battery, closed contact of relay 24, conductor 27, left make contact of relay 28, transfer key 14, conductors 29 and 29', filaments of lamps 10, 11 and 13 to ground, thereby causing the illumination of said lamps. The energization of relay 28 also closes a circuit through its right make contact from battery, conductor 30, winding of relay 19 to ground. This circuit causes the operation of relay 19, which completes a circuit from ground through its front make contact, over conductors 31 and 32 and through signals 15, 16, 17 and 18 in parallel to battery, causing each of these signals to operate and indicate a busy condition.

In response to the lighting of lamps 10 and 11, the operator will insert a plug with 60

the customary cord circuit in jack 6. Battery is connected to the sleeve of this plug, and a circuit is completed over the sleeve of jack 6, conductor 33, winding of relay 24 to ground. The closure of this circuit causes the operation of a relay 24 which closes its contacts and opens the circuit by which ringing relay 22 is energized, and also the circuit over which lamps 10, 11 and 13 are lighted. The opening of these circuits causes the de-energization of relay 22 and the extinction of lamps 10, 11, and 13. The operation of relay 24 also causes the de-energization of relays 26 and 28. Relay 19 which was energized by a circuit controlled by these relays, is now maintained operated by relay 24, by a circuit from battery, front contact of relay 24, conductor 30, winding of relay 19 to ground.

20 The incoming call will be completed at the position where jack 6 is located, when possible, or transferred by means of key 14 to some other position where it can be completed in a well understood manner.

25 At the completion of the call, the cord circuit is dissociated from the jack in which it is plugged and the circuit by which relay 24 was energized will be broken, this relay releasing. The release of relay 24 causes the release of relay 19 of the signaling circuit. Relay 19, upon releasing, closes a short-circuit from ground through its armature and upper make contact, spring 20, spring 21, conductor 32 to battery. This circuit is only 30 momentarily established, but sufficient time is allowed to place ground potential on the battery side of the tubes to effectively short-circuit them and re-establish the normal high internal resistance of the tubes. The normal high resistance characteristics of the tubes are thus re-established, and the false and continued operation of the tubes by a grounded circuit caused by leakage through adjacent conductors is eliminated.

40 While there is shown and described herein in a certain preferred form of the invention by way of illustration, it will be understood that it is not limited or confined to the precise details of construction herein described and delineated, as modification and variation may be made within the scope of the claims without departing from the spirit of the invention.

What is claimed is:

55 1. A signaling circuit including a plurality of discharge tubes connected therewith, a relay associated with the signaling circuit operable to establish a current path over one side thereof to cause the simultaneous operation of said tubes, and means responsive to the release of said relay for short-circuiting said tubes over the other side of said circuit.

60 2. A signaling circuit including a plurality of discharge tubes connected therewith, relay means for closing said signaling cir-

cuit to operate said tubes, a short-circuit for said tubes associated with the signaling circuit, and means controlled by the release of the relay means for momentarily closing said short circuit.

3. A signaling circuit including a plurality of neon tubes connected therewith, a relay associated with the signaling circuit operable over one side thereof to cause the simultaneous operation of said tubes, and means responsive to the release of said relay for short-circuiting said tubes over the other side of said circuit.

4. A signaling circuit having a plurality of discharge tubes connected therewith, said discharge tubes being of high resistance, a relay associated with the signaling circuit operable to impress sufficient potential on one side thereof to operate the discharge tubes, and means responsive to the release of said relay for short-circuiting said discharge tubes over the other side of the signaling circuit to re-establish their high resistance.

5. A signaling system comprising a plurality of pairs of conductors having a cable covering, a series of discharge tubes connected in parallel to each pair of conductors, a relay associated with each pair of conductors and operable to establish a current path over one side thereof to cause the simultaneous operation of said discharge tubes, and means responsive to the release of said relay for short-circuiting said discharge tubes over the other side of said circuit to return them to normal condition and prevent their continued operation by a grounded circuit provided by leakage through adjacent conductors in the cable.

6. A signaling system comprising a plurality of pairs of conductors having a cable covering, a series of discharge tubes connected in parallel to each pair of conductors, said discharge tubes being normally of high resistance, a relay associated with each pair of conductors and operable to impress sufficient potential over one side thereof to cause the simultaneous operation of said discharge tubes, by breaking down the high resistance characteristics of the tubes and maintaining comparatively low resistance therein, and means responsive to the release of said relay for short-circuiting said discharge tubes over the other side of said circuit to re-establish the high resistance of the discharge tubes and prevent their continued operation by any grounded circuit which may be provided by leakage through adjacent conductors in the cable.

7. A signaling system comprising a plurality of pairs of conductors having a cable covering, a series of discharge tubes of normally high resistance connected in parallel to each pair of conductors, relay means associated with each pair of conductors for

closing a circuit thereover to operate its associated tubes, a short circuit for said tubes associated with each pair of conductors and means controlled by the relay means for momentarily closing the short circuit to permit the return of the discharge tubes to normal condition and prevent their false operation

by any grounded circuit which may be provided by leakage through adjacent conductors in the cable.

13

In testimony whereof, I have signed my name to this specification this 14th day of March 1927.

SAMUEL P. SHACKLETON.
